UNITED STATES PATENT OFFICE

HECTOR MACKNIGHT, OF EAST ORANGE, NEW JERSEY, ASSIGNOR TO CORNELIA CANFIELD

BATHROOM CABINET

Application filed October 12, 1929. Serial No. 399,191.

This invention relates to a cabinet designed for a bath room and has for its object, broadly, to provide a cabinet arranged to contain all articles and supplies generally needed or required in a bath room used by a single family and making allowance for guests.

It is an object of the invention to provide a bath room cabinet of such proportions that it will occupy a limited floor space, but which will provide ample storage room for every needed article. Another object is to provide such an arrangement that all of the parts will be convenient in use.

Still another object is to provide a cabinet of symmetrical and pleasing design which may be portable or may be built in a building as a permanent fixture having compartments of such proportions that they may contain large or limited supplies of articles corresponding to the quantity or kind required for use.

It is an object of the invention to provide, as an additional feature, a bath room cabinet which may be constructed of sheet metal, plain or enameled having parts which will be accessible for cleaning and maintenance in a sanitary condition.

The invention includes a bath room cabinet having extensible parts and includes a stool for containing various toilet articles and supplies and adapted to be removed from the cabinet for use or to be stored therein. One of the specific objects in view is to provide a new article of manufacture for the purposes mentioned, consisting of parts which may be conveniently manufactured and assembled.

With the foregoing objects in view, and others to be mentioned the invention presents a new and useful construction, combination and arrangement of parts as described herein and claimed, and as illustrated in the accompanying drawings, it being understood that changes may be made in form, size, proportion of parts and minor details, said changes being within the scope of the invention as claimed.

In the drawings, Fig. 1 is a perspective view of a bath room cabinet embodying my invention. Fig. 2 is a view of the same in front elevation. Fig. 3 is a transverse section on

line 3—3 of Fig. 2. Fig. 4 is a transverse section on line 4—4 of Fig. 2. Fig. 5 is a transverse section on line 5—5 of Fig. 2. Fig. 6 is a transverse section on line 6—6 of Fig. 2. Fig. 7 is a perspective view of a stool, being a separable part of the cabinet. Fig. 8 is an end view of the bath cabinet. Fig. 9 is an enlarged detail, being a top plan view of a vertically adjustable clothes hanger. Fig. 10 is a detail illustrating, in perspective, one of the uses of the removable stool.

Referring now to the drawing for a more particular description, I provide a bath room cabinet preferably of rectangular form in plan and elevation, its top, sides, back and bottom being indicated respectively at 11, 12, 13 and 14.

In order that ample space may be provided for a supply of towels for family use and that a similar supply may be provided for guests, two separate sections A and B (Fig. 2) are provided in the upper part of the cabinet, each consisting of a rear compartment 15 and a front compartment 16, said compartments being separated by intermediate doors 17, racks 18 being provided for the rear compartments 15 and racks 19 being mounted on the inner sides of the doors 20 of said sections.

The rear compartments 15 are adapted to contain bath towels, and the front compartments 16 are for containing face cloths and face towels, and this arrangement permits the required separation of these towels, and provides a convenient access to the towel supply to members of a family or for guests.

Towels in use or the clothing of a person while bathing may be hung on the horizontal slide-rods 21 or upon the vertical adjustable hook-rods 22.

Numerals 23 indicates a hamper arranged to be swung forwardly on its hinges 24 at the bottom of the cabinet, and it will be appreciated that such a container is convenient for many purposes in a bath room since in many instances storage should be provided temporarily for articles to be laundered.

Numerals 25 indicate a pair of drawers adapted to be used for storage of small towels or wash cloths not generally hung on

racks, and at 26 are indicated a pair of swing-drawers adapted to contain toilet preparations, instruments, cosmetics or medicines.

Numeral 27 indicates a rectangular recess formed in the cabinet adjacent to the hamper for receiving a rectangular stool 28, and since the recess 27 has no bottom the castors 29 of the stool may engage the floor of the bath room and the stool may be moved outwardly from or moved into the recess as may be required.

It is considered that, by use of the stool, the cabinet will be complete to supply every article needed in a bath room. This stool may be used not only as a seat while dressing but may contain brushes and shoe-polishing material; also since it is provided with compartments 30 and a door α closing said compartments it may contain such needed articles as hot water bags, electrical pads, or a supply of toilet soaps.

Numeral 31 indicates a wing-cover or pad which has a connection at 32 with the top of the stool to permit it to swing and to lie upon the top of the stool for use when polishing shoes, and which serves to prevent injury or soiling of the top of the stool, said pad or wing being provided with a depression 33 for receiving the sole or heel of the shoe during the operation of cleaning or shoe-polishing. Numeral 34 indicates a recess formed in the vertical wall of the stool for receiving the pad or wing when not in use so that it will not be obtrusive.

As best shown in Figs. 8 and 9 of the drawings, the apertured brackets 35 which support the hook-rod 22 are each provided with a slot 36 opening on its aperture and therefore this rod may have vertical sliding movements in the brackets and may be adjusted vertically to dispose its hooks or prongs above the cabinet as shown in Figs. 1 and 8, or may be disposed as shown in Fig. 2, when not used, the prongs of said rod moving through the slots 36 while making said adjustments. After an adjustment has been made the rod may be rotated in a limited arc so that the prongs will not be disposed in line with the slots, and when thus disposed the rod and its hooks or prongs will support any required weight.

As best shown in Fig. 3 of the drawing, collars or sleeves 37 are provided for the inner side walls of the cabinet so that the slide-rods 21 will be maintained in approximately a horizontal position. However, this is not important if these rods are mounted in such a manner that they will be disposed closely adjacent to the top wall 11 of the cabinet.

While I have shown only a single hook-rod 22 and four slide-rods 21, the number may, of course, be changed if desired.

Numeral 38 indicates a drawer intended for use as a container for combs and hair brushes,

and a mirror (not shown) is generally used in connection with the cabinet, and is placed on the top, adjacent to the guard rail 39 of said cabinet.

It is considered that, in the present instance, provision has been made for storage of all toilet articles and supplies generally used in a bath room, and that the arrangement of parts is such that they will be convenient in use. It will be appreciated that the cabinet may be installed in bath rooms of small size, and could be built into the wall of a bath room if desired.

The advantages in the use of cabinets generally and particularly of kitchen cabinets is that they provide a specific place for every needed article coupled with convenience in use, and the present invention, it is believed, provides these same advantages for bath rooms.

I claim as my invention,—

A cabinet for holding bathroom accessories in orderly array comprising a cabinet structure having towel compartments in the upper portion of the same, a forwardly swinging hamper for used towels and the like hingedly supported in the base portion of the cabinet structure at one side and below the towel compartments, the opposite side of the cabinet structure along side the forwardly swinging hamper having a compartment open to the bottom and front of the cabinet structure, a self-supporting box stool housing in said open compartment and withdrawable from the front of the cabinet structure at the side of the forwardly swinging hamper and a swing drawer opening at the front of the cabinet structure over the top of said stool housing compartment for the use of an occupant of the stool when the stool is withdrawn from the compartment.

In testimony whereof, I have affixed my signature.

HECTOR MACKNIGHT.
